Primary Examiner — Philip S Hyder*Assistant Examiner* — Darlington Ly(74) Attorney, Agent, or Firm — Calfee, Halter & Griswold, LLP(57) CLAIM

The ornamental design for a display screen or portion thereof with graphical user interface and icons, as shown and described.

DESCRIPTION

The FIGURE is a front view of a display screen or portion thereof with graphical user interface and icons of the new design.

The broken lines showing a display screen or portion thereof form no part of the claimed design.
